UNITED STATES PATENT OFFICE

2,374,799

OIL BURNER

John Bilan, Flint, Mich.

Application June 5, 1944, Serial No. 538,777

2 Claims. (Cl. 158—91)

The present invention relates to oil or other liquid fuel burners, and has for its principal object to provide an improved oil burner.

A still further object of the present invention is to provide means in an oil burner for facilitating prompt consumption of the oil which may be spilled.

Another object of the present invention is to provide a novel draft regulating means in an oil burner.

With the above general objects in view and others that will appear as the invention is better understood, the same consists in the novel construction, combination and arrangement of parts hereinafter more fully described and illustrated in the accompanying drawing and pointed out in the appended claims.

In the drawing forming a part of this application, and in which like designating characters refer to corresponding parts throughout the several views;

Fig. 1 is a cross-sectional view through the oil burner taken on line 1—1 of Fig. 2; and

Fig. 2 is a top elevational view of the oil burner, partly in section.

Referring to the present drawing in detail there is shown therein a housing comprising a pair of parallel side plates 10. Integrally formed with said plates 10 and in transverse relation therewith is a pair of inclined walls 11 which are arranged in a V-shaped formation as is clearly seen in Fig. 1. The upper end of each of said walls 11 connects with a horizontal ledge 12. The outer ends of each of said ledges 12 integrally connect with upwardly projecting walls 13, which in turn connect, by their upper ends with horizontal cover plates 14, each of the latter being in spaced, parallel relation with ledges 12.

Said ledges 12, walls 13 and plates 14 are preferably integrally connected with plates 10, and constitute housings 15.

Adjacent the upper end of each wall 11 is an integrally formed ledge 16 which upwardly and angularly projects from each of said walls 11, for defining trough 17 within which a quantity of oil or other liquid fuel is adapted to be received and consumed.

Centrally of each trough a fuel supplying pipe 18 is connected from underface of each wall 11. Said pipes 18 at their lower ends connect with pipes 19, which extend one plate 10 and outwardly therefrom connect with a single pipe 20, which in turn, centrally thereof, connects with manifold 21.

Upon the inner face of each wall 11 and below 55

ledge 16, lining 22, preferably made of asbestos or other impervious material, is provided, for the purpose of absorbing any fuel that may have spilled out from trough 17 and over ledge 16, to be consumed thereon before the same escapes from walls 11.

The draft regulating means for the burner comprises a V-shaped element 23 consisting of a pair of inclined walls 24 receivable between the inclined walls 11 and in a parallel relation therewith. The upper ends of said walls 24 extend slightly above plates 10 and their upper ends overlie the mouths of housings 15 so as to deflect combustion gases and smoke into said housings 15.

Provided in cover plates 14 is a plurality of vents 25, with each of which a pivoted closure 26 is adapted to cooperate. These closures 26 may be shifted to close said vents 25, to partially close the vents or entirely open the same, or close one or more of them entirely, for the purpose of regulating, retarding or enhancing the combustion of liquid fuel in trough 17, depending upon the amount thereof and other factors, and for regulating the draft in conjunction with the draft regulating element 23.

Adjacent the apex, defined by the lower ends of said walls 24 is a transverse bar 27 having a stud 28 made at a central point thereof, to receive in a swiveled connection the lower end of screw 29, having its upper end threaded and extended in a threaded relation through a transverse bar 30, which is integrally formed with the upper edges of plates 10. Knob 31 is received by the upper end of said screw 29 and above said bar 30. By virtue of this arrangement it will be seen that screw 29 may be shifted in a vertical direction by rotating the same by means of knob 31. This shifting movement will bring the draft regulating element 23, including its walls 24, to or away from the cooperating faces of walls 11. It is observed that the walls 24 are at all times in parallel relation with walls 11 and the spaces therebetween constitute the draft passages for air, which flows into the opening defined by the lower spaced edges of walls 11, and thereupon passes between said walls 24 and 11 and past ledges 16 and into housings 15. The air enhances the combustion of fuel in troughs 17 and carries with it the combustion gases into housings 15, while some of the gases may pass through crevices defined by the free edges of cover plates 14 and the adjacent upper ends of walls 24.

It is further observed that when the draft regulating element 23 is brought down as far as it will

go by driving screw 28, walls 24 will contact with ledges 16, in which event the air passages defined by said walls 24 and 11 will be closed and the flame in and above trough 17 will be extinguished. Although this may constitute one means for extinguishing the flame in the burner, a preferable means for extinguishing the flame is to stop the flow of oil into the manifold 21 by closing the valve in association therewith, thereby assigning to the draft regulating element 23 the function for which it is primarily designed.

The oil is fired by dropping a match through crevices defined by the free inner ends of cover plates 14 and the adjacent upper ends of walls 24, or through vents 25.

From the hereinabove description it will be apparent that by raising or lowering the draft regulating element 23, and thereby shifting the same to or away from the walls 11, the air passages defined by walls 24 and 11 will be respectively narrowed or enlarged for the purpose of regulating the amount of air necessary for proper consumption of oil in trough 17 and consumption of smoke and gases in housings 15.

The oil burner herein described is intended for positioning within a stove 32 indicated by dotted lines in Fig. 2.

While there is described herein a preferred embodiment of the present invention, it is nevertheless to be understood that minor changes may be made therein without departing from the spirit and scope of the invention as claimed.

What I claim as new is:

1. A liquid fuel burner comprising an inclined wall, a container carried thereby, said container being adapted to receive a constant supply of liquid fuel upon which the same is adapted to be consumed, a housing carried by the upper end of

said wall, said housing being provided with a mouth overlying the upper end of said wall, a draft regulating wall substantially in parallel relation with said first named wall, the upper end of said second named wall overlying said mouth, and means for shifting said draft regulating wall toward or away from said first mentioned wall for regulating the amount of air passing between the two walls and past said container and into said housing through said mouth, said housing being provided with vents through which combustion gases may pass from said housing outwardly.

2. A liquid fuel burner comprising a pair of inclined walls, the upper ends of said walls being farther spaced from each other than the lower ends thereof, said lower ends of said walls defining a slot for passage of air into the burner, troughs made in the upper ends of said walls for receiving a constant supply of liquid fuel and in which the same is adapted to be consumed, a V-shaped draft regulating member positioned between said walls, said member including a pair of inclined walls, each in substantially parallel relation with one of said first named walls, said walls of said draft regulating member being joined at their lower ends to define an apex, said apex overlying said slot substantially centrally thereof for the purpose of dividing the air passing through said slot into two streams and directing each stream to pass into one of the two passages defined by said first named walls and said walls of said draft regulating member, and means for shifting said draft regulating member toward or away from said first named walls for regulating the size of passages therebetween.

JOHN BILAN.
